DESIGN FOR A VACUUM BOTTLE

Carl Bramming, Alexandria, Ind., assignor to
The Mantle Lamp Company of America, Chi-
cago, Ill., a corporation of Illinois

Application May 22, 1939, Serial No. 85,125

Term of patent 14 years

To all whom it may concern:

Be it known that I, Carl Bramming, a citizen
of the United States of America, residing at
Alexandria, in the county of Madison and State
of Indiana, have invented a new, original, and
ornamental Design for Vacuum Bottles, of which
the following is a specification, reference being
had to the accompanying drawing, forming a part
thereof.

The figure is a view in front elevation of a
vacuum bottle, showing my new design.

I claim:

The ornamental design for a vacuum bottle,
substantially as shown.

CARL BRAMMING.
